UNITED STATES PATENT OFFICE

WAYNE S. SMITH, OF MERCED, CALIFORNIA

AUTOMATIC STARTER SWITCH

Application filed June 11, 1930. Serial No. 370,101.

This invention relates to motor vehicles and particularly to a mechanism for controlling the operation of the starter motor.

The principal object of my invention is to provide an automatically functioning switch structure governed by the operation of the engine itself by means of which the engine will be turned over and restarted if it stalls for any reason, without any attention on the part of the driver being necessary. Also the

mere closing of the engine ignition switch, if the vehicle has not been already running, will immediately cause the starter motor to function.

15 By means of the improved switch therefore not only are ordinary starting operations facilitated but the annoyance and hazards due to the engine stalling as it sometimes does in traffic and other places will be avoided, as 20 will be evident, and the necessity for a starting pedal or a hand switch other than that also used to close the engine ignition circuit is eliminated.

25 The automatic starter switch is also constructed so that as soon as the engine is turned over and is operating under its own power the switch will be automatically opened so that the starter motor will cease to function until the occasion for its use again arises.

30 A further object of the invention is to produce a simple and inexpensive device and yet one which will be exceedingly effective for the purpose for which it is designed.

35 These objects I accomplish by means of such structure and relative arrangement of parts as will fully appear by a perusal of the following specification and claims.

40 In the drawings similar characters of reference indicate corresponding parts in the several views.

45 Fig. 1 is a side outline of an automobile engine of a certain make showing the mounting of my improved starter switch in connection therewith.

Fig. 2 is a sectional elevation of the switch detached.

50 Fig. 3 is a fragmentary view showing the operation of the governor control catch.

Fig. 4 is a diagram of the circuit in which the switch is interposed.

Referring now more particularly to the characters of reference on the drawings the numeral 1 denotes a shaft adapted to be 55 driven from the engine 2, preferably at a somewhat greater speed than the crankshaft of the engine. In different engines different ways must of course be employed to drive this shaft.

60 In the present instance I have shown the shaft as being interposed between the generator 3 and the pump 4 of the engine, and forming a connection between the shafts thereof, so as to be driven by whichever one of said shafts is itself driven by the engine.

65 Adapted to be mounted on the engine case or other fixed member is a bracket 5 from which sleeves 6 project parallel to the shaft. These sleeves are insulated and spaced from each other and while not necessarily in the opposed relation shown are preferably the same distance from the shaft radially of the same.

70 Spring pressed contacts 7 are slidable in the sleeves and are positioned to simultaneously engage a continuous contact ring 8 disposed concentric with the shaft on a disc 9 which is mounted on a hub 10 slidably keyed on the shaft. Adjustably fixed on the shaft some distance from the disc in the direction away from the contacts is a collar 11 having opposed arms 12 pivoted thereon and carrying weights 13 on their outer ends. Pairs of links 14 extend between the hub 10 and the arms 12 intermediate the ends of the latter and are pivoted to both. The above structure, as will be evident, forms a speed controlled governor, the parts of which are preferably arranged and proportioned so that the contacts 7 will be engaged by the ring 8 only when the governor arms are in their idle or at-rest position, at which time the weights bear against the links as shown in Fig. 2.

75 A light compression spring 15 disposed about the shaft between the collar and hub acts to move the governor to an idle position and the hub and disc unit to a contact engaging position. The relative effectiveness of the weights and spring is also such that the weights will

only move to such full idle position when the speed of the shaft 1 is practically nil.

The circuit to the starter motor 16 of the engine comprises a lead 17 extending from the battery 18 to one of the sleeves 6 with a hand switch 19 interposed therein, and another lead 20 from the other sleeve to the motor. The switch 19 is also interposed in the engine ignition circuit EC so that the one switch serves both to close the engine circuit and initially close the starter motor circuit.

By means of the above construction it will be seen that whenever the engine stops the contacts 7 will be engaged by the ring 8 and the circuit to the starter motor will be closed, assuming that the switch 19 is also closed. The starter motor will be thus automatically energized and as soon as the shaft 1 is rotating at a predetermined speed the governor 25 will act to withdraw and hold the contact ring disc away from the contacts, breaking the circuit to the motor until the engine again stops, when the operations are repeated. If it is intentionally desired that the motor shall not be turned over it is only necessary to open the switch 19 which at the same time opens the engine ignition circuit. This feature avoids the possibility of the ignition switch being left closed after the engine stops and 30 it is not desired to start it again, as is now frequently the case and which of course soon exhausts the battery.

The governor preferably ceases to function and thus causes the starter motor circuit to be closed only when the shaft 1 is practically stationary. A very slight increase in the speed of the shaft would therefore cause the governor to function to break the circuit, before the engine was actually running under its own power, were not some means provided so that a greater shaft speed is necessary to start the governor functioning than that which causes it to stop functioning. Such means is constructed as follows:

45 A catch dog 21 is pivotally connected with each pair of links just beyond the corresponding weight, being shaped to partially project over such weight when the latter is at rest so as to prevent the outward movement of the weight without swinging the dog a certain distance back. A snap action spring 50 22 between the link and dog acts either to hold the latter in a weight engaging position or clear of the path of the same, after the weight has once pushed its way past the dog, as shown in Fig. 3. A stop nub 23 provided with the dog on the side of the pivot opposite the weight is arranged to engage the link and act to limit the movement of the dog away 55 from the weight so that the spring will be only a very slight distance past dead center. Another nub 24 projects from the dog adjacent the link and under the path of the weight to be engaged by said weight as the latter 60 reaches its at-rest or idle position, so as to

then cause the dog to be swung from its retracted position to a weight engaging one. The spring 22 being preferably only just past dead center it offers little resistance to such movement by the weight, but is arranged so that it must be expanded a considerably greater distance to allow the weight to push past the same when once engaged thereby. The governor is therefore held inoperative until the speed of the shaft 1 is such that a centrifugal force is generated by such speed to enable the weights to overcome the spring action and move outwardly past the dogs. Said dogs will then remain in their retracted positions until with the slowing down of the shaft the weights again approach said dogs and cause them to move to a weight engaging position, as above described.

70 The entire mechanism above described, with the exception of the ends of the shaft, are preferably enclosed by a removable housing 25 supported by the bracket 5.

75 From the foregoing description it will be readily seen that I have produced such a device as substantially fulfills the objects of the invention as set forth herein.

80 While this specification sets forth in detail the present and preferred construction of the device, still in practice such deviations from such detail may be resorted to as do not form a departure from the spirit of the invention 85 as defined by the appended claims.

85 Having thus described my invention what I claim as new and useful and desire to secure by Letters Patent is:

100 1. An automatic switch for the starter motor of an engine including a shaft adapted to be driven by the engine, spaced contacts arranged for interposition in the motor circuit, a contact ring member engaging the contacts when the shaft is stationary, a governor structure mounted on the shaft and connected to the member to draw the latter away from the contacts when the governor functions with the rotation of the shaft, said governor being in its fully idle or contracted position 105 when said member is engaged with the contacts, and means arranged in connection with said governor for resisting the functioning of the governor when once in such idle position until the shaft has attained a predetermined speed while permitting the governor to move unrestrainedly to said fully idle position with a lesser speed of the shaft.

110 2. An automatic switch comprising a driven shaft, spaced contacts adapted to be interposed in a circuit, a contact ring slidable on the shaft to engage the contacts when the shaft is stationary, a governor structure mounted on the shaft, and arms pivoted at one end and having fly-balls on their other ends, said arms being arranged to swing outwardly with the rotation of the shaft from a predetermined idle position relative to the shaft when the latter is stationary, means 115

connecting said arms to the ring to draw the latter away from the contacts with the outward swinging of the arms, catch dogs mounted in connection with the ring positioned to 5 engage and engagingly actuated by the balls when the latter assume their idle position, and spring means acting on the dogs to resist the outward swinging movement of the arms.

3. An automatic switch comprising a 10 driven shaft, spaced contacts adapted to be interposed in circuit, a contact ring slideable on the shaft to engage the contacts when the shaft is stationary, a governor structure mounted on the shaft, and arms pivoted at one 15 end and having fly-balls on their other ends, said arms being arranged to swing outwardly with the rotation of the shaft from a predetermined idle position relative to the shaft when the latter is stationary, means connect- 20 ing said arms to the ring to draw the latter away from the contacts with the outward swinging of the arms, catch means to yieldably engage the balls as the latter reach their idle position, and spring means yieldably 25 acting on said catch means with a greater pressure in a ball releasing direction than in a ball engaging direction.

In testimony whereof I affix my signature.
